UNITED STATES PATENT OFFICE.

CHARLES S. BIRD, OF WALPOLE, MASSACHUSETTS.

SHINGLE.

1,184,509.

Specification of Letters Patent. Patented May 23, 1916.

Application filed February 5, 1913. Serial No. 746,354.

To all whom it may concern:

Be it known that I, CHARLES S. BIRD, a citizen of the United States, residing at Walpole, in the county of Norfolk and State of Massachusetts, have invented certain new and useful Improvements in Shingles, of which the following is a specification.

My present invention pertains to improvements in shingles, the construction and advantages of which will be hereinafter set forth, reference being had to the annexed drawings, wherein:

Figure 1 is a perspective view of several of the shingles produced in accordance with my invention; Fig. 2 a perspective view of one of the shingles viewed from the under side, and partly broken away to more clearly illustrate the construction; and Fig. 3 a like view, the parts being shown in full, illustrating a slightly modified form of the structure.

The object of the present invention is to produce a paper shingle having a butt materially thicker than the opposite end thereof, the butt presenting an unbroken surface and being of a thickness sufficient to form the shadow effect which is essential to a commercial article.

The shingle may be said to comprise a main body member, formed of an upper section 1, folded upon itself and producing an underlying short section 2. At the joint or line of fold between the two layers 1 and 2, I introduce a filler, as 3, composed of a fibrous cord or small rope, and preferably between the sections 1 and 2 there is introduced a separate section 4 which at the butt end of the shingle contacts with the adjacent face of the member 3. Said member 4 may be made of a length equal to the length of the member 2, or if desired it may be made of a different length, as for instance, longer, as indicated at 4^a in Fig. 3.

The members 1, 2 and 4 are preferably formed of paper, suitably waterproofed as by treatment with asphaltum or the like, and they are bound together by a suitable cementitious material in the course of manufacture, being subjected to sufficient pressure to cause adhesion of the various parts of the structure throughout.

The filler 3, when formed of cord or rope, will likewise be saturated with asphaltum or any other water-repellant material, so

that the structure as a whole is waterproof throughout.

By producing the upper and lower faces of the shingle from a single sheet of material and folding the same at the butt there is produced a butt which is without joint or seam except at the edges of the shingle, said butt being sufficiently stiff and rigid to prevent the shingle from turning upwardly under stress of weather and at the same time the thickened butt produces the very desirable shadow effect which is present in the ordinary roof laid up with wooden shingles.

An objection to paper shingles which has hitherto obtained lies in the fact that the butt usually presents a seam or joint which, in winter, due to the action of water freezing upon the shingles and in the seams of the butt, or in summer, due to the intense heat which is present when the sun is shining directly upon the roof, causes the butt to open up and thereafter to be further loosened through the action of the wind. With the present shingle such objection does not obtain, for there are no seams at the butt of the shingle into which the water can enter, and consequently the opening up due to freezing or the action of the wind cannot take place.

The interposition of the member 4 between the upper and lower layers 1 and 2 obviates any sharp line of bend in the layers 1 and 2 adjacent the filler 3, and in addition tends to thicken the lower or butt end of the shingle.

Having thus described my invention, what I claim is:

1. As a new article of manufacture, a shingle having a thickened butt, composed of a sheet of waterproof material folded upon itself at the butt end of the shingle, with a narrow filler strip interposed at the butt end only between the layers thus produced, the parts being secured together by the employment of cementitious material.

2. As a new article of manufacture, a shingle having a thickened butt, composed of waterproof paper comprising two layers formed from a single sheet folded at its butt end about a fibrous filler strip formed of cord or rope located at the butt end of the shingle, the under layer extending to a considerable distance along the under face of the upper layer but stopping short of the

upper end thereof, and being secured thereto by cementitious material.

3. As a new article of manufacture, a shingle having a thickened butt, said shingle comprising a sheet of paper folded upon itself and embracing at the folded butt portion of the shingle a cord or rope, the under layer of said sheet stopping short of the upper end of the upper layer; and a section of paper embraced between the upper and lower layers adjacent the butt proper,

all of said parts being formed of waterproof material and permanently secured to each other by a suitable cementitious material.

In testimony whereof I have signed my 15 name to this specification in the presence of two subscribing witnesses.

CHARLES S. BIRD.
